UNITED STATES PATENT OFFICE.

HENRY W. BELDSMEIER, OF ST. LOUIS, MISSOURI.

BUTTER-TUB, &c.

SPECIFICATION forming part of Letters Patent No. 693,217, dated February 11, 1902.

Application filed June 12, 1901. Serial No. 64,233. (No model.)

To all whom it may concern:

Be it known that I, HENRY W. BELDSMEIER, a citizen of the United States, residing at St. Louis, Missouri, have invented a new and useful Improvement in Butter-Tubs and the Like, of which the following is a specification.

My invention consists of the novel features herein shown, described, and claimed.

Figure 1 is a view in elevation of a butter-tub or the like constructed in accordance with the principles of my invention. Fig. 2 is a plan of the parts shown in Fig. 1. Fig. 3 is a vertical section. Fig. 4 is a view showing the means of fastening the cover. Fig. 5 is a view analogous to Fig. 4, on an enlarged scale, showing a bayonet-joint and lock, the other parts being broken away. Fig. 6 is a plan of the locking device in its unlocked or open position. Fig. 7 is a view analogous to Fig. 6 and showing the parts in their locked positions. Fig. 8 shows one of the bayonet-joints which has no lock on an enlarged scale. Fig. 9 is an enlarged sectional detail of the inner cover. Fig. 10 is a horizontal section showing a modified construction of the tub, parts being broken away.

Referring to the drawings in detail, the tub has staves 11, the bottom 12, and the outer hoops 13. A cross 14 is placed upon the bottom 12 to support the lining 15. Ribs 16 are fastened against the inner faces of the staves 11, and the lining 15 rests against these ribs, thus forming air-spaces under and around the lining—that is, between the lining and the bottom of the tub. The cover 17 closes the lining, and the handle 18 is attached to this cover. The cover 19 closes the body of the tub, and the hoop or flange 20 of this cover has portions bent outwardly to form the ears 21, arranged suitable distances apart, and the slots 22 extend horizontally from the ears all in the same direction. The upper hoop of the tub is metal, and the pins 23 extend outwardly from this hoop in position to extend into the ears 21 when the cover is placed in position, and when the cover is slightly rotated the pins pass into the slots 22, thus forming a bayonet-joint connection between the tub and the cover. The spring-

strap 24 is attached to the flange 20 and operates in the horizontal slot 25 in one of the ears 21 and has an opening 26 to receive one of the pins 23. The button 27 is attached to the flange 20 in position to engage the free end of the strap, and one end of said button is adapted to hold the strap locked with the pin and the other end of said button is adapted to hold the strap unlocked. The screw 28 is screw-seated in the handle 18, and the washer or plate 29 is fastened to the head of the screw 28 above the handle. An opening 30 is formed through the cover 19 in vertical alinement with the screw 28 and to receive the head, so that when all the parts are in position a screw-driver may be inserted through the opening 30 to operate the screw 28 to force the plate 29 upwardly against the lower face of the cover 19 and hold the cover 17 and the lining 15 in position.

In Fig. 10 the tub is shown made up of alternate thick and thin staves, thus producing air-spaces around the lining without the use of the ribs 16.

If preferred, vertical ribs or blocks may be used instead of the ribs 16. In any event the lining is removable. If desired, water, ice, or sawdust or other suitable filling may be placed in the air-space around the lining.

I prefer to make the body of the tub of wood and the lining of granite-iron.

The tub may be used for shipping butter or oysters or other similar purposes.

I claim—

1. In a butter-tub or the like, a main body, a removable lining mounted in the main body with air-spaces around the lining, a removable cover for the lining, a removable cover for the main body, means of securing the body-cover rigidly in position and adjustable means of securing the lining and lining-cover rigidly in position, said means being adjustable after the body-cover is secured in position, substantially as specified.

2. In a butter-tub or the like, a main body, a removable lining mounted in the main body with air-spaces around the lining, a removable cover for the lining, a removable cover for the main body, means of securing the

body-cover rigidly in position and adjustable means of securing the lining and lining-cover rigidly in position, said means being adjustable after the body-cover is secured in position, said means consisting of a screw seated in the lining-cover in alignment with an opening in the body-cover and a plate fixed on

5 said screw to engage the body-cover, substantially as specified.

HENRY W. BELDSMEIER.
